BURNER STRUCTURE AND SYSTEM

Elroy M. Rulsey, Milwaukee, Wis., assignor to Cleaver-Brooks Company, a corporation of Wisconsin

Filed Apr. 16, 1957, Ser. No. 651,192

3 Claims. (Cl. 158—28)

This invention relates to oil burners utilizing fuel oil and atomizing air, and particularly to pilot burners therefor also utilizing fuel oil and atomizing air.

This application is a continuation-in-part of my co-pending application Serial No. 585,252, filed May 16, 1956, and now abandoned.

It is a general object of the invention to provide a new and improved apparatus of the character described.

In oil burners of relatively high capacities, ignition of the main burner is commonly accomplished by first establishing, by means such as an electric circuit, a gas pilot flame, which in turn ignites the main oil flames. Gaseous fuel is not always available, however, and may even be prohibited in certain areas by local codes. In such cases, other means must be provided for igniting the main oil flame.

While ignition of the main flame directly with an electric circuit is satisfactory for low fuel rates, since the heat generated by the circuit is small and localized, it may not be sufficient to ignite the main flame when the oil burning rate is relatively high. When the oil flow rate is high, if the flame is not established almost immediately when flow starts, an unsafe condition exists because a relatively large amount of oil can flow into the combustion chamber in only a few seconds, and in its highly atomized state can cause an explosion if ignited from the heat of the refractories. Thus, direct ignition by electric circuit is not always satisfactory.

Another method of ignition is by means of an oil pilot. In such arrangements, an electric circuit ignites a low flow rate of atomized fuel oil in a separate nozzle which in turn ignites the main flame. The low flow rate is easily ignited by the electric circuit and if for some reason ignition does not occur, oil accumulates in only small quantities which do not create an unsafe condition, since the rate of flow is low and since controls may be provided to delay the main oil flow until the pilot is established.

Oil pilots of the character described commonly employ a pressure atomizing nozzle, that is, a nozzle effective to atomize the oil at the pressure under which it is supplied to the nozzle. Such nozzles have only a small orifice in the tip to limit flow, and often plug with carbon formed by unburned oil in the nozzle when subjected to high radiation temperatures from the main flame and refractories. Further, a pressure atomizing nozzle requires relatively high pressure (in the nature of 100 p.s.i.) for satisfactory atomization, so that in furnaces utilizing low pressure oil and air under pressure for atomizing the oil at the main burner, a booster pump must be provided to establish the proper oil pressure at the pilot nozzle. In such installation, the necessity for a booster pump may be obviated by providing a pilot which utilizes low pressure oil and air under pressure for atomizing the oil.

With the above and other considerations in mind, it is a more specific object of the invention to provide a new and improved system for supplying fuel oil and

2

atomizing air to a pilot burner nozzle for lighting a main burner also utilizing fuel oil and atomizing air.

Another object is to provide a new and improved system of the character described in the preceding paragraph wherein fuel oil may be supplied to the pilot burner from the oil lines supplying the main burner, and atomizing air may be supplied to the pilot burner from the lines supplying air to the main burner.

In systems of the character described, the volumes and pressures of oil and air required at the pilot burner are substantially less than those desired at the main burner and must be regulated to obtain proper combustion at the pilot burner.

Accordingly, a further object is to provide a new and improved system of the character described, including means for regulating the flows of air and oil to the pilot burner nozzle.

Fire tube boiler constructions conventionally include a fire tube which functions as a combustion chamber in which a main burner nozzle is removably supported by means independent of the fire tube, and such mounting means may permit removal of the main burner from the fire tube for inspection purposes without the necessity of opening the head of the boiler. However, these constructions have also included a pilot burner for the main burner mounted in the fire tube refractories in a manner that required opening the boiler head to provide access to the pilot burner. Such arrangements involved considerable time and labor expense during shut down periods for inspection, maintenance and repair of the pilot burner.

With these considerations in mind, it is also an object of the invention to provide an integrated main burner nozzle and pilot burner nozzle structure which is readily accessible and removable as a unit for maintenance and repair.

Another object is to provide a new and improved burner structure of the character described in the preceding paragraph wherein the main burner is separately retractable, leaving the pilot burner in position.

Other objects and advantages will become readily apparent from the following detailed description taken in connection with the accompanying drawings, in which:

Figure 1 is a fragmentary, vertical, longitudinal sectional view illustrating a boiler construction utilizing an integrated main and pilot burner structure embodying the principles of the present invention;

Figure 2 is a fragmentary elevational view of the boiler construction and integrated burner structure illustrated in Figure 1, taken at about the line 2—2 of Figure 1;

Figure 3 is an elevational view of the burner structure illustrated in Figures 1 and 2, taken at about the line 3—3 of Figure 1;

Figure 4 is a diagrammatic illustration of a system embodying the principles of the present invention;

Figure 5 is a view similar to Figure 1, illustrating a modified integrated main and pilot burner structure, wherein the main burner is separately retractable;

Figure 6 is an elevational view, taken at about the line 6—6 of Figure 5; and

Figure 7 is an elevational view, taken at about the line 7—7 of Figure 5.

While illustrative embodiments of the invention are shown in the drawings and will be described in detail herein, the invention is susceptible for embodiment in many different forms, and it should be understood that the present disclosure is to be considered as an exemplification of the principles of the invention and is not intended to limit the invention to the embodiment illustrated. The scope of the invention will be pointed out in the appended claims.

Referring now to the drawings, Figures 1, 2 and 3 illustrate an integrated main burner and pilot burner mounting structure 10 embodying the principles of the present invention and adapted for use in the combustion chamber of a fire tube boiler. As seen in Figure 1, portions of the boiler are illustrated, including a boiler shell 11 which is conventionally provided with a header plate (not shown) for supporting the ends of tubes forming multiple passes for combustion gases through the boiler, and for supporting a fire tube having an end portion 12 which projects beyond the header plate and to the end of the boiler shell 11. The end portion 12 of the fire tube is provided internally with an annular ring 13 of refractory material adjacent the area of combustion in the fire tube. The end of the boiler shell 11 is closed by a door structure which may be removably bolted on the end of the boiler shell or hingedly mounted thereon to permit access into the boiler shell. As illustrated, the door structure for closing the end of the boiler shell includes a closure plate 14 lined internally with refractory material 15 adjacent the area of the fire tube 12, and a dish-shaped closure member 16 overlying the plate 14.

The plate 14 is formed with a circular opening 17 adapted to receive the end portion of a tubular burner housing member 18 which receives the burner structure and forms with the fire tube 12 a combustion chamber 19. An annular, outwardly extending flange 21 on the tubular burner housing 18 abuts against the closure plate 14 about the opening 17. The dish-shaped closure member 16 is formed with a circular opening 22 aligned with the opening 17 in the plate 14 and adapted to receive the end of a hollow cylindrically-shaped part 23 projecting outwardly from the member 16 and adapted to be secured thereto by means such as bolts or screws (not shown) passing through a mounting flange 24 and the member 16. The left end of the tubular burner housing 18 (as viewed in Figure 1) is formed with an outwardly extending annular flange 26 adapted to be secured by means not illustrated to the cylindrical part 23. In use, the door member 16 may be removed from the position illustrated, taking with it the tubular burner housing 18, after which the door member 14 may be removed to provide access to the interior of the boiler shell, all without the necessity of dismounting the burner structure 10 from the member 16.

The door members 14 and 16 serve to define an air plenum chamber to which secondary air may be supplied by means not illustrated to support combustion at the burners. Secondary air passes from the air plenum chamber into the burner housing member 18 through air inlet openings 18' in the member 18.

The integrated main burner and pilot burner mounting structure 10 includes a mounting plate 26 adapted to be secured to the door of the boiler by means such as screws (not illustrated) passing through the holes 27 (Figure 3), through the flange 26 and into the hollow cylindrical projecting part 23. The mounting plate 26 supports a main burner 28 and a pilot burner 29 by means to be described presently.

The main burner 28 is an integral structure formed of a cluster of three burner nozzles 30a, 30b and 30c (Figs. 1 and 2). Fuel oil is supplied to the main burner 28 by means of a pipe 31, and atomizing air is supplied to the main burner by an outer concentric air supply pipe 32. The main burner 28 is supported by means of a threaded connection with the air supply pipe 32. The fuel oil supply pipe 31 is rigidly supported in the air supply pipe 32, and the two pipes pass through the center of the mounting plate 26, with the air supply pipe 32 being rigidly secured to the plate 26 by means such as a press fit of the pipe in the central opening 33 in the plate. Externally of the combustion chamber, the oil supply pipe 31 is provided with a fitting 35 adapted for connection with a suitable source of fuel oil. Simi-

larly, externally of the combustion chamber, the air supply pipe 32 is provided with a fitting 36 adapted to be connected with a suitable source of air under pressure. If desired, the fitting 36 may be supplied with a suitable gauge 37 for indicating air pressure.

The pilot burner 29 includes a single burner nozzle 38 and is provided with a threaded air supply pipe 39 rigidly connected to and supporting the pilot burner. The burner also includes a fitting 40 connected with a fuel oil supply line 41. The pilot burner fuel supply line 41 is connected through the medium of a reducer 42 to a fitting 43 described more fully hereinafter. The fitting 43 is connected with a ball check valve 44 which is in turn connected with a pipe length 45 threadedly mounted in and passing through the mounting plate 26 and preferably provided, externally of the combustion chamber, with a fitting 46 adapted to be connected with a suitable source of fuel oil supply as explained more fully hereinafter. Air under pressure for atomizing the fuel oil at the pilot burner 38 is supplied, according to the present invention, to the pilot burner air inlet pipe 39 by means of an air supply line 48 connected with the pipe 39 through the medium of a reducer 49 and connected by means of a fitting 50 with the air chamber in the main burner 28 ahead of the point at which air and fuel oil are mixed as described more in detail presently.

The pilot burner 29 is supported by means of a mounting bracket including an end portion 52 which is received on the air supply pipe 32 for the main burner 28 and retained in position by means such as the set screw illustrated at 53. The pilot burner mounting bracket projects from the air supply pipe 32 and includes an opposite end portion 54 which receives the pilot burner air supply pipe 39 which may be retained in position in the bracket by means such as the set screw illustrated at 55. In this manner the pilot burner is supported integrally with the main burner and may be adjustably positioned relative to the main burner.

The burner structure illustrated includes an electric ignition means for the pilot burner comprised of a pair of electrodes 56 each including an insulating outer portion having an electrically conductive sparking element 57 passing therethrough. The electrodes are mounted on the pilot burner mounting bracket in split clamping portions 59 adapted to be clamped about the outer insulating portion of the electrodes by means of clamping screws 60. Each of the electrically conductive sparking elements 57 includes a hook-shaped conductive connector 61 adapted to be connected with a coiled conductor 62. The coiled conductors 62 are connected respectively with hook-shaped connector ends 63 of conductive posts 64 each embedded in an insulating sleeve 65. The insulating sleeves 65 are suitably fixed in the mounting plate 26 and pass therethrough, and the posts 64 provide exposed terminals outside the combustion chamber for connecting the sparking elements with a suitable source of power. By loosening the clamping bolts 60, the position of the electrodes 56 may be adjusted to properly position the sparking elements 57 relative to the pilot burner nozzle 58, and the coiled conductors 62 permit such adjustment while maintaining a circuit.

The main burner 28 and the pilot burner 29 are additionally supported in proper positions in the combustion chamber by means of radially projecting support rods 68 threadedly mounted in the end portion 52 of the pilot burner mounting bracket and engageable with the interior wall of the tubular burner housing 18.

It will be appreciated that the burner construction described above incorporates into a single structure a main burner and a pilot burner therefor, both burners being supported by means of the mounting plate 26, and therefore readily removable from the combustion chamber simply by dismounting the plate 26. Prior art constructions have conventionally mounted the pilot burner

in portions of the boiler or furnace proper, such as in the refractory 13 of the fire tube 12, so that the pilot burner was not easily accessible for maintenance and repair, but required opening up the front head of the boiler, such as by removal of the plates 14 and 16 forming the door construction described. The arrangement disclosed provides for mounting of the main burner and the pilot burner in a manner such that both are readily accessible to provide substantial savings in time and labor expenses for maintenance and repair of the boiler.

Referring now particularly to Figure 4, the integrated burner mounting structure described may be utilized in a system including a fuel oil supply pump 70 having its inlet connected by means of a line 71 with a suitable fuel supply tank, a portion of which is represented by the bracket 72 which mounts the line 71. The fuel oil supply pump 70 has its outlet connected with a line 73 having a fuel oil strainer 74 and leading to a fuel oil metering valve 76. When there is no call for fuel at the burner, fuel oil is returned to the tank through a line 77 connected with the metering valve 76 and the tank bracket 72.

The line 77 includes a back pressure valve 78 adapted to regulate the pressure of the fuel oil at the valve 76, such pressure being readable on a gauge 79 connected in the line 73.

Fuel oil is supplied from the metering valve 76 to the main burner 28 by means of a line 80, a solenoid controlled shut off valve 81 and a line 82 suitably connected with the fitting 35 (illustrated in Figure 1) which communicates with the main burner 28.

Air under pressure is supplied to the main burner 28 for atomizing the fuel oil by means of a compressor 83 which takes air in through an air cleaner 84, a manually controllable valve 85 and a check valve 86. Air is pumped from the compressor 83 to an oil sump pit 87 which functions as an air receiver and lubricating oil separator. Lubricating oil passes to the compressor 83 through a line 88 which includes a lubricating oil strainer 89. Atomizing air passes from the separator 87 through a line 90 to the fitting 36 (Figures 1 and 2) which communicates with the air supply pipe 32 leading to the main burner 28.

According to the present invention, the pilot burner 29 is supplied with fuel oil from the main burner fuel oil supply line 73 through a line 92 having a solenoid controlled shut off valve 93 suitably connected with the pipe section 45 (Figure 1), the fitting 43, and the line 41 which is connected with pilot burner 29. In order to obtain the proper oil volumes and pressures at the pilot nozzle, the flow of oil to the pilot nozzle is controlled by means of a restrictive orifice 94 of predetermined size provided on the fitting 43. This represents an extremely simple means for supplying oil to the pilot burner in metered quantities and at regulated pressures.

Air is supplied to the pilot burner under pressure for atomizing the fuel oil at the pilot burner nozzle 38 by means of an air supply line 48, previously described, which leads from the air chamber of the main burner 28. In order to obtain the proper air volumes and pressures at the pilot nozzle 38, the flow of air to the pilot nozzle is controlled by means of the air supply line 48. More specifically, the line 48 is one of predetermined cross sectional passage area and of predetermined length to provide the desired pressure drop at the pilot nozzle. This represents an extremely simple arrangement for supplying atomizing air to the pilot burner, and for controlling the flow of air in metered quantities to the nozzle to obtain the desired mixture of fuel oil and atomizing air for efficient combustion.

In operation, the system illustrated may be controlled entirely automatically if desired so that when the boiler calls for heat, the fuel pump 70 is immediately started, and oil circulates through the loop including the lines 71, line 73, the strainer 74, the metering valve 76, line 77 and back pressure valve 78. Oil pressure of the desired

value is established against the solenoid controlled valve 93 by means of the back pressure relief valve 78, and this pressure may be read on the gauge 79. In a system of the character illustrated, the pressure referred to may be approximately 40 p.s.i.

At the time the boiler calls for heat and the pump 70 is started, the compressor 83 may also be started, and air is delivered through the separator 87, the line 90, the pipe 32, and to the main burner 28. In the system illustrated, the pressure drop through the main burner nozzle 30 may be about 16 p.s.i., for example, and this pressure may be read on the gauge 37. At the same time, air is supplied from the main burner 28 to the pilot burner 29 through the air supply line 48. Ignition and combustion of the mixture of air and atomized fuel oil at the pilot burner 29 is most efficient in a system of the character described when the pressure drop through the pilot nozzle 38 is about 10 p.s.i., for example. In order to obtain the desired pressure drop at the pilot nozzle 38, the amount of air supplied to the pilot nozzle is controlled by means of the air supply line 48, as previously described. In the system illustrated, the line 48 is comprised of a tube of $\frac{1}{8}$ " outside diameter, with a .030" wall thickness and the length may be controlled to regulate the pressure drop.

When the boiler calls for heat, and the pump 70 and compressor 83 are started, the controlling monitor (not illustrated) may automatically open the solenoid controlled valve 93 in the pilot burner fuel oil supply line. With air already being supplied at the pilot burner 29, opening the valve 93 provides a fuel oil supply to the nozzle 38. In order to obtain an efficient combustion at the pilot nozzle 38, the flow of fuel oil to this nozzle is controlled by the orifice 94, as previously described. In a system of the character described, the pressure drop in the oil flow at the nozzle 38 should desirably be at about 10 p.s.i., for example. In the system illustrated, the orifice 94 is of a predetermined size such that for a pressure drop thereacross of about 30 p.s.i., for example, a flow of fuel oil of about 2 g.p.h. is obtained at the pilot nozzle.

After the solenoid valve 93 is opened, the automatic controls may complete a circuit to the pilot burner sparking elements 57 to ignite the pilot flame. When the pilot flame is ignited, the controls may be effective to open the solenoid controlled main fuel oil valve 81 to establish an oil flow at the main burner. When the flame at the main burner is ignited by the pilot flame, the solenoid controlled pilot fuel valve 93 is closed and the pilot flame is extinguished. Air from the main burner continues to flow through the pilot nozzle so long as the main flame is burning, and this functions to keep the pilot nozzle cool and clean so that it can not plug with carbon.

When the boiler no longer calls for heat, the valve 81 is closed, and the pump 70 and compressor 83 are stopped.

Supplying atomizing air to the pilot burner nozzle from the main burner air supply lines through the use of a calibrated pressure drop tube avoids the need for additional valves, regulators and fittings and thus provides substantial economies. Supplying fuel oil to the pilot burner from the main burner supply lines eliminates the necessity of a separate fuel oil supply tank, additional pumps and fittings and also represents substantial economies.

While the burner structure and system disclosed have been illustrated in connection with a fire tube boiler, it should be understood that the invention is by no means limited to fire tube boilers, but will have utility in other boilers and furnaces; the fire tube boiler has been chosen merely to illustrate one manner in which the invention may be utilized.

Referring to Figures 5, 6 and 7, I have illustrated a modified burner mounting structure for use in a com-

bustion chamber similar to that illustrated at 19 in Figure 1. As illustrated in Figure 5, a combustion chamber 19a is formed in part by a tubular shaped housing member 18a having inlet openings 18a' for admitting secondary air, and an annular mounting flange 26a.

The modified burner structure includes a main burner nozzle 100 and a pilot burner nozzle 101 both supported by means of a mounting plate 103. The mounting plate is adapted to be secured in position on the mounting flange 26a, closing one end of the combustion chamber, by means of screws or bolts (not illustrated) receivable in holes 104 provided in the mounting plate and in cooperating openings (not illustrated) in the mounting flange 26a.

In this modification, the main burner 100 and the pilot burner 101 are removable with the mounting plate as an integral unit, in a manner similar to that illustrated in Fig. 1. Also, the modification of Figure 5 provides for retraction of the main burner separately, leaving the pilot burner and the mounting plate in position. Accordingly, a support for the main burner is provided in the form of a rigid tubular part 106 which passes through the mounting plate 103 and is rigidly secured therein in a suitable manner. One end portion 107 of the tubular support is positioned so as to project into the combustion chamber 19a when the plate 103 is mounted, and the opposite end portion 108 of the tubular support projects from the opposite side of the mounting plate, exteriorly of the combustion chamber.

As in the modification of Figure 1, the main burner nozzle 100 is supplied with fuel oil under pressure by means of a supply pipe 110, and is supplied with atomizing air under pressure by means of an outer concentric supply pipe 111. The pipes 110 and 111 are rigidly secured together in spaced concentric relationship and at the ends adjacent the single main burner nozzle 100, rigidly support the nozzle. The outer air supply pipe 111 and the main burner nozzle 100 are of an outer diameter which permits these parts to be telescoped within the tubular support member 106, and the pipe 111 includes a fixed collar 112 adapted to slidably engage the interior of the tubular support 106. Thus, the main burner nozzle and its supply pipes 110 and 111 are removably positioned in the tubular support 106, and are removably held in position by a set screw in the end portion 108 of the tubular support adapted to engage the outer pipe 111.

End portions of the supply pipes 110 and 111 project exteriorly of the mounting plate beyond the end 108 of the tubular support, as illustrated in Figure 5. The end of the inner, oil supply pipe 110 projects slightly beyond the end of the air supply pipe 111, and is provided with a fitting 115 adapted to be connected with a suitable source of oil under pressure, such as the oil supply pipe 82 illustrated in Figure 4. The end of the outer concentric air supply pipe is provided with the fitting 116 adapted to be connected with a suitable source of air under pressure such as the air supply line 90 illustrated in Figure 4. If desired, the fitting 116 may be provided with means for connecting a suitable pressure gauge 117.

In order to support the pilot burner nozzle 101, a mounting bracket 119 is slidably fitted on the exterior of the tubular support 106, and may be adjustably retained in position by set screws such as that illustrated at 120. The mounting bracket 119 is formed with two depending ear portions 121 and 122 (Figure 6) which are split for the purpose of releasably clamping suitable sparking igniter elements which may be retained in adjusted positions by means of clamping screws 123. The split ear portions 121 and 122 include depending leg portions 124 and 125 both of which are joined with an annular collar 126 for supporting the pilot burner nozzle 101. The pilot burner nozzle may be retained in adjusted positions in the collar 126 by means of a clamping screw 127.

In a manner similar to that illustrated in Figure 1,

oil under pressure is supplied to the pilot burner nozzle through a fitting 130 on the side of the nozzle and a supply line 131. The pilot burner fuel supply line 131 is connected through the medium of a reducer 132 to a fitting 133 which may include an orifice forming means similar to that illustrated at 43 and 94 in Figure 1. The fitting 133 is in turn connected with a ball check valve 134 which includes an inlet passing through the mounting plate, rigidly secured in the latter, and terminating in a fitting 135 adapted to be connected with a suitable source of oil under pressure such as the supply line 45 illustrated in Figure 4.

Since the main burner nozzle 100 in the modification of Figure 5 is separately retractable, without the pilot burner, the pilot air supply line cannot be connected with the main burner supply line as in the illustrations of Figures 1 and 4. Instead, air under pressure is supplied to the pilot burner nozzle 100 through a reducer 137 which is connected to an inlet line 138 which passes through the mounting plate, is rigidly secured therein, and terminates in a fitting 139 adapted to be connected with a suitable source of air under pressure. Preferably, the fitting 139 should be connected with the main air supply line 90 exteriorly of the combustion chamber at a position near the elbow bend adjacent the fitting 36 in Figure 4.

As in the modification of Figure 1, the fuel supply line and the air supply line for the pilot burner 101 are formed to, or include means to, receive fuel and air under pressure from the main burner supply lines and deliver these to the pilot burner nozzle at reduced pressures and volumes relative to those at the main burner. Thus, the principles of operation described in connection with Figures 1 and 4 also apply to the modification of Figure 5.

In a manner similar to that described in connection with the modification of Figure 1, in Figure 5, the bracket 119 is adapted to releasably and adjustably support electrical sparking elements 141 and 142 which are suitably encased in insulating sleeves 143 receivable in the split clamping ears 121 and 122. The conductive sparking elements 141 and 142 each terminate at the ends remote from the nozzle in hook-shaped connector portions 144. Coiled, spring-like, extensible connectors 145 are connected to the end portions 144 and to insulated conductors 146 which are supported in the mounting plate 103, extend therethrough, and terminate in exteriorly positioned taps 147 which are accessible for connection with a suitable source of power.

In addition to the mounting bracket 119, a supporting bracket 149 is slidably fitted on the tubular support 106, and may be releasably retained in adjusted positions thereon by means of set screws 150. The supporting bracket 149 is in the form of a spider having three radially extending legs 151 equally spaced angularly about the bracket. The legs may be provided, at the ends, with means to engage the inner surface of the tubular housing 18a, or the ends of the legs may directly engage the part 18a. As illustrated, the legs 151 are utilized to support a diffuser element 152 which is generally dish-shaped, having a cylindrical sidewall portion 153 and diffuser portions 154 for directing secondary air toward the main burner nozzle 100.

The diffuser is attached to the legs 151 by having arcuate segments 155 of the cylindrical wall 153 slotted as at 156, deformed inwardly, out of round, and secured to the legs 151 by screws 157. The cylindrical sidewall 153 fits slidably in the tubular housing 18a.

It will be understood that the burner structure illustrated in Figures 5, 6 and 7 may be connected in a system such as that illustrated in Figure 4, so that the advantages attributed to the system of Figure 4 also apply to the structure of Figures 5, 6 and 7. The modification of the latter figures, in addition to providing an integrated main burner and pilot burner removable as a unit, also permits separate retraction of the main burner.

I claim:

1. In an oil burning system for a fire tube boiler or the like having a combustion chamber, in combination, a main burner oil atomizing nozzle for receiving fuel oil under pressure and oil atomizing air under pressure and passing the same in an atomized mixture to the combustion chamber, means providing a source of fuel oil at a predetermined constant pressure, a main burner fuel supply line connecting the source of fuel oil and the main burner nozzle to deliver oil to the nozzle at a predetermined pressure, means providing a source of atomizing air at a predetermined constant pressure, a main burner air supply line connecting the source of air and the main burner nozzle for delivering air to the nozzle at a predetermined pressure, a pilot burner oil atomizing nozzle adjacent the main burner nozzle for receiving fuel oil under pressure and oil atomizing air under pressure and passing the same in an atomized mixture to the combustion chamber to light the main burner, a pilot burner fuel supply line connecting the pilot burner nozzle and the source of fuel oil to supply fuel oil to the pilot burner nozzle, a fixed flow restrictor and pressure reducer in the pilot burner fuel supply line for reducing the fuel pressure to a predetermined value at the pilot burner nozzle less than the oil pressure at the main burner nozzle, and a pilot burner air supply line connecting the pilot burner nozzle and the main burner air supply line to supply atomizing air to the pilot burner nozzle, said pilot burner air supply line having a predetermined cross-sectional passage area and a predetermined length providing a predetermined invariable capacity for reducing the air pressure to a predetermined value at the pilot burner nozzle less than the air pressure at the main burner nozzle.
  2. In an oil burning system for a boiler or the like having a combustion chamber, in combination, a main burner oil atomizing nozzle for receiving fuel oil under pressure and oil atomizing air under pressure and passing the same in an atomized mixture to the combustion chamber, means for supplying fuel oil to the main burner nozzle at a predetermined constant pressure, means providing a source of atomizing air at a predetermined constant pressure, a main burner air supply line connecting the source of air and the main burner nozzle for delivering air to the nozzle at a predetermined pressure, a pilot

- burner oil atomizing nozzle adjacent the main burner nozzle for receiving fuel oil under pressure and oil atomizing air under pressure and passing the same in an atomized state to the combustion chamber to light the main burner,

5 means for supplying fuel oil to the pilot burner nozzle at a predetermined constant pressure less than the pressure of oil at the main burner nozzle, a pilot burner air supply line connecting the pilot burner nozzle and the main burner air supply line to supply atomizing air to the

10 pilot burner nozzle, and a fixed flow restrictor and pressure reducing means in the pilot burner air supply line for reducing air pressure to a predetermined value at the pilot burner nozzle less than the pressure of air at the main burner nozzle.

15 3. In an oil burner system for a boiler or the like having a combustion chamber, in combination, a main burner oil atomizing nozzle for receiving fuel oil under pressure and oil atomizing air under pressure and passing the same in an atomized mixture to the combustion chamber,

20 20 means providing a source of fuel oil at a predetermined constant pressure, a main burner fuel supply line connecting the source of fuel oil and the main burner nozzle to deliver oil to the nozzle at a predetermined pressure, means for supplying atomizing air to the main burner

25 25 nozzle at a predetermined constant pressure, a pilot burner oil atomizing nozzle adjacent the main burner nozzle for receiving fuel oil under pressure and an oil atomizing air under pressure and passing the same in an atomized mixture to the combustion chamber to light the main burner,

30 30 a pilot burner fuel supply line connecting the pilot burner nozzle and the source of fuel oil to supply fuel oil to the pilot burner nozzle, a fixed flow restrictor and pressure reducer in the pilot burner fuel supply line for reducing the fuel pressure to a predetermined value at the pilot

35 35 burner nozzle less than the oil pressure at the main burner nozzle, and means for supplying atomizing air to the pilot burner nozzle at a predetermined constant pressure less than the air pressure at the main burner nozzle.
